[57] CLAIM

The ornamental design for a perpetual calendar, substantially as shown and described.

DESCRIPTION

FIG. 1 is a perspective view of a perpetual calendar showing my new design;

FIG. 2 is a front elevational view, the opposite side thereof being plain and unornamental;

FIG. 3 is a right side elevational view;

FIG. 4 is a bottom plan view; and

FIG. 5 is a perspective view of a modified form of the perpetual calendar, the opposite side being plain and unornamental.

*FIG. 1.**FIG. 2.**FIG. 3.**FIG. 4.**FIG. 5.*
